ELECTRIC DISCHARGE DEVICE

Ernest A. Massa, Jr., Haddon Heights, N. J., assignor to Radio Corporation of America, a corporation of Delaware

Application March 31, 1936, Serial No. 71,855

10 Claims. (Cl. 250—27.5)

This invention relates to electric discharge devices and particularly to devices of the type wherein amplification of a primary electron current is obtained through utilization of secondary emission.

More specifically, the invention relates to improvements in electron multipliers of the general type disclosed in the copending application of Ernest A. Massa et al., Serial No. 33,996, filed July 31, 1935, and assigned to Radio Corporation of America.

In the Massa application, there is disclosed a multi-stage electron multiplier constituted by a plurality of pairs of opposed electrodes axially disposed in an evacuated container with their faces lying in parallel planes. For convenience, the electrodes may be designated, respectively, "upper" or "accelerating" and "lower" or "multiplying". Preferably, the faces of the multiplying electrodes are specially treated as by photo-sensitization, to enhance their ability to emit secondary electrons, and a primary electron source, photoelectric or thermionic in character, is provided. In addition, electromagnetic means are provided for the purpose of causing the electrons to describe approximately trochoidal paths from each lower electrode to the next adjacent electrode, thus permitting the use of high accelerating potentials on the upper electrodes without the disadvantages resulting from the space charges encountered in a device constructed according to the prior art.

The ratio of the number of secondary electrons to the number of primary electrons depends, in part, upon the character of the surface and upon the potential difference between the surface and the source of the electrons that impinge upon it. This ratio can be made considerably greater than unity. For example, a ratio of five or more secondary electrons to one impinging electron is readily obtainable with metallic surfaces treated in known ways and subjected to discharges at potentials of 200 to 400 volts.

If the secondary electron current, in turn, is caused to impinge with sufficient velocity upon a further electrode with a suitably treated surface, the ratio of secondary emission from the second multiplying electrode may also be greater than unity. Hence, one is able to obtain with n multiplying electrodes in cascade, for example, an amplification of the original or primary modulated or unmodulated electron current equivalent to the amplification per electrode raised to the n th power.

A multi-stage electron multiplier is capable of

giving an amplification of several million times the primary current. Where such relatively enormous gains are achieved in a single envelope there is a pronounced tendency for the device to break into oscillation and to generate spurious and undesired frequencies of oscillation. This phenomenon is thought to obtain by reason of the inherent internal coupling existing between the collecting plate and the several multiplying electrode elements but may be the result of other less apparent causes peculiar to such high gain devices.

It is, accordingly, an object of the invention to obviate the generation of so-called "feed-back oscillations" in devices of the type wherein amplification of a primary electric current is obtained through utilization of the phenomenon of secondary emission.

Another object of the invention is to provide an electron multiplier, the operation of which is characterized by substantial freedom from distortion.

The above and other objects are accomplished in accordance with the invention by the provision of an auxiliary electrode in the form of a grid positioned in the path of the secondary electrons and preferably directly connected to the accelerating electrode nearest the collecting plate or anode of the device. The grid is preferably of special design and is so positioned with respect to the anode as to present a substantially negligible barrier to the passage of the electrons.

The novel features characteristic of the invention are set forth with particularity in the appended claims. The invention itself, however, both as to its organization and its method of operation, together with additional objects and advantages, will be best understood from the following description of certain specific embodiments thereof, when read in connection with the accompanying drawing, in which

Figure 1 is a diagrammatic representation of a multi-electrode photo-sensitive electron multiplier embodying the invention,

Fig. 2 is an end-view and Fig. 3 is a side elevation of an electrode assembly including one type of grid,

Fig. 4 is an end view and Fig. 5 is a side elevation of an electrode assembly including a grid of preferred alternate construction,

Fig. 6 is a plan view of the pattern formed upon the output electrode by the electrons which have passed through the grid of Figs. 4 and 5, and

Fig. 7 is a chart of the plate characteristics of

a ten-stage multiplier including a grid of the type illustrated in Figs. 4 and 5.

An electron multiplier constructed in accordance with the principle of the invention is diagrammatically illustrated in Fig. 1. Light entering the tube 5 and striking a photo-sensitive electrode 10 releases primary electrons which are drawn upward by an electrostatic field, provided by the upper or accelerating electrode 20 but are deflected by a constant magnetic field (from a source not shown) perpendicular to the plane of the paper. When the voltages and field are properly adjusted the adjacent lower or "multiplying" electrode 11 is struck by the group or bundle of primary electrons, emanating from the primary emitter 10, and secondary electrons are emitted. The secondary electrons from the point of impact encounter electrical conditions substantially identical to those met by the primary electrons and become increasingly more numerous as they impinge successively upon the multiplying electrodes 12-15. After several such steps the output is taken from the target or anode 45 at the opposite end of the tube. Back-coupling and the generation of "feedback" oscillations is prevented, in accordance with the invention, by the provision of an auxiliary electrode 35 which may be directly or indirectly connected to the accelerating electrode 25 nearest the output electrode 45. This auxiliary electrode 35 is of grid-like construction and extends downward towards, but not touching, the last multiplying electrode 15 in a plane normal thereto and directly across the path of the multiplied electron stream.

While various types of grid construction will prevent the tube from oscillating, it has been found that when it is of ordinary meshed construction the output current will usually be distorted. Thus, it was found that a 30 mesh screen built of .006" nickel wire included in a ten-stage multiplier tube connected to a load of 70,000 ohms prevented the tube from oscillating, but harmonic distortion was found to be substantially 28% at 0.28 watt output. The per cent distortion was discovered to be a function of the quantity of electron current absorbed by the screen. The current absorbed varies with the voltage applied to the collector, especially when the voltage applied to the collector approaches the voltage applied to the screen.

It was found that absorption and attendant distortion are reduced when the grid is of open work construction, with the grid-wires spaced one from another a distance corresponding substantially to the distance between the plane of the wires and the plane of the output electrode. Preferably, the area of the wires presented to the electron beam is less than substantially 5% of the cross-sectional area of the beam and optimum performance is achieved when the wire area is approximately 2% of the cross sectional area of the electron beam.

Figs. 2 and 3 show a grid constructed and positioned in the above described preferred manner. In these figures the grid is constituted by a frame 35a, suspended from the upper accelerating electrode 25, and having a plurality of spaced parallel wires 35b, 35c, etc. spanning the path of the electrons in a vertical direction. These wires 35b-35c, etc. are spaced one from another a distance substantially equal to the distance from the plane of the grid and the plane of the output electrode 45 (Fig. 3). In a "standard" tube this distance may ordinarily be of the order of $\frac{1}{16}$ of an inch.

The grid 35' of Figs. 4 and 5 is constituted by a continuous wire 35w which crosses and re-crosses the path of the electrons in a horizontal direction. Where the tube is provided with a pair of spaced insulating strips M-M' of mica or the like (as in application Serial No. 33,996) for supporting the paired electrodes 15' and 25', these strips are provided on each side with a pair of orifices n through which the wire 35w is threaded. One terminal of this wire is connected as indicated at 35t, to the upper or accelerating electrode 25' and the other end conveniently bent over the mica strip M as indicated at 35s. The sections of the grid wire 35w like the spaced wires 35b-35c of Figs. 2 and 3 are spaced one from another a distance substantially equal to the distance from the plane of the grid and the plane of the output electrode 45.

In operation, the grid wires appear to concentrate and to direct the electrons in the manner of an electron-lens, so that when observed in a dark room the electron pattern on the output electrode 45 has a well defined luminous portion 45p (Fig. 6) between the grid wires. It is believed that the electrons "bend" around the wires instead of impinging against them. In any event the wires are preferably of the order of .001-.005 inch in diameter so that they absorb a minimum amount of current.

The plate characteristics of a ten-stage electron multiplier including the grid of Figs. 4 and 5 and formed of .001 tantalum wire spaced $\frac{1}{16}$ " from the collector, are shown in the chart of Fig. 7. The plate current, measured in milliamperes at different values (1, 2 and 4) of light intensity, is represented along the ordinate of the chart and plate voltage, with respect to screen or grid voltage, is represented along the abscissa of the chart. Line A-C represents the load on the output of the tube (in ohms) which determines the amount of R. M. S. power obtained from the tube. Point B on line A-C coincides with a point midway along the ordinate between zero and maximum light intensity. Zero distortion would be achieved if B were also the midpoint of AC, but this ideal condition can only obtain where the curves of light intensity extend straight to the zero ordinate, as would be the case if the screen collected absolutely no current when the plate voltage approaches the screen voltage.

From the foregoing it is apparent that the percentage of harmonic distortion may be mathematically expressed by the formula

$$\frac{AB-BC}{AB} \times 100$$

and applying this formula in the instant case a quantitative value of 2.9% at .27 watt (output) is obtained.

The various embodiments of the invention which have been illustrated for the purpose of explaining the inventive concept are susceptible of various modifications which will be apparent to those skilled in the art.

What is claimed is:

1. An electron tube comprising, an electrode surface adapted to liberate electrons by secondary emission, a collector electrode, an accelerating electrode for directing electrons from said surface to said collector electrode, and a control member connected to said accelerating electrode and positioned in the path of said electrons.

2. An electron tube comprising, an electrode surface adapted to liberate electrons by secondary emission, a collector electrode, an accelerating electrode for directing electrons from said

surface to said collector electrode and a control electrode of grid-like construction connected to said accelerating electrode and positioned in the path of said electrons and presenting a substantially negligible barrier to the passage of said electrons.

3. The invention as set forth in claim 2 wherein in the area presented to the electrons of the wires constituting said grid-like electrode is less than 10 substantially 5% of the cross-sectional area of the path of said electrons.

4. The invention as set forth in claim 2 wherein in the area presented to the electrons of the wires constituting said grid-like electrode is of 15 the order of substantially 2% of the cross-sectional area of the path of said electrons.

5. An electron tube comprising, an electrode surface adapted to liberate electrons by secondary emission, a collector electrode, an accelerating 20 electrode for directing electrons from said surface to said collector electrode, and a grid-like member connected to said accelerating electrode and positioned in the path of said electrons, the wires constituting said grid-like member being 25 spaced one from another a distance substantially equal to the distance between the plane of said wires and the plane of said terminal electrode.

6. The invention as set forth in claim 5 wherein in said grid-like electrode is constituted by a 30 metallic frame and a plurality of wires each parallel with the others and joined to said frame.

7. The invention as set forth in claim 5 wherein in said grid-like member is constituted by a continuous wire crossing and recrossing the path of said electrons.

8. An electron tube comprising, a pair of oppositely located parallelly arranged insulating strips, an electrode surface adapted to liberate electrons by secondary emission, an accelerating electrode spanning said strips and supported thereby, a terminal electrode positioned to receive electrons 10 from said emissive surface, and a grid-like member in the path of said electrons and supported by said strips and connected to said accelerating electrode.

9. The invention as set forth in claim 8 wherein in said strips are provided with a plurality of orifices and said grid-like member is constituted by a continuous wire passing through said orifices and crossing and recrossing the path of said electrons.

10. An electron multiplier comprising a plurality of secondary-electron emitters, means for directing electrons from one to another of said emitters, an output electrode interposed in the path of the secondary-electrons, and a foraminous electrode mounted closely adjacent said output electrode for subjecting the secondary-electrons to an oscillation suppressing potential.
